THOMAS BRATTAN, OF BIRKENHEAD, ENGLAND, ASSIGNOR TO A. H. DIXSON.

Letters Patent No. 99,285, dated February 1, 1870.

IMPROVEMENT IN GAS-METERS.

The Schedule referred to in these Letters Patent and making part of the same.

To all whom it may concern:

Be it known that I, THOMAS BRATTAN, of Birkenhead, in the county of Chester, England, have invented certain new and useful Improvements in Gas-Meters; and I do hereby declare that the following is a full and exact description thereof.

My invention relates to what is known as the ordinary wet meter, and overcomes the principal objections to this cheap, and durable, and highly-desirable form of gas-measuring apparatus. It insures a uniformity in the water-level in the meter for a long period, makes this level adjustable within as wide limits as are ever required in practice, insures a sufficient reservoir or fountain to keep the water at this level for a long period, without requiring attention, and in case the fountain shall, through long neglect, get low, gives warning of the fact, by a diminution in the force of the gas, without the disagreeable flickering or jumping of the lights which is commonly observed.

I will first proceed to describe what I consider the best means of carrying out my invention, and will afterward designate the points which I believe to be new.

The accompanying drawings form a part of this specification.

Figure 1 is an end view of the meter, with the face of the front casing removed, and the interior casing shown in section, to give a view of its arrangement and effect;

Figure 2 is a vertical section through the filling-tube and drainage-passage, showing, also, all the parts beyond; and

Figure 3 is a parallel section through the interior casing.

The figures represent the novel parts, with so much of the ordinary parts as is necessary to show their relations thereto.

Similar letters of reference indicate like parts in all the figures.

Tints are employed merely to aid in distinguishing parts, and do not imply necessary differences of material.

The material of all the novel parts may be tinned iron and brass or white metal.

A represents the cylindrical case which contains the wet gas-meter wheel. I have not thought it necessary to represent this old and familiar portion of the apparatus. It may be in the ordinary approved form.

The shaft b, projecting from the end of the case, is turned by the meter-wheel, by the levity of the gas.

The water-line in the interior of the case A is indicated by m m. This is the level at which the meter-wheel will perform with absolute correctness; and it is desirable to hold the water exactly at this level, under all conditions, for a long period.

To effect this, I store a considerable quantity of water in the outside casing A¹, and use it as a reservoir from which to supply the main casing A, as evaporation or other cause shall render necessary.

The water-line in the exterior casing A¹ is higher than that in the interior or main casing A, and is indicated by n n.

The water is supplied to the outside casing at long intervals, through the pipe a', which leads down nearly to the bottom of the casing, and effectually prevents the escape of any air or gas.

A small rectangular casing, A² A³, is mounted within the casing A¹. Its upper half is divided by a semi-partition, extending downward from the top in the centre, as represented. This, in effect, divides this inner casing into two chambers, the left and the right, which are indicated, respectively, by the letters A² A³.

The right chamber A³ communicates with the interior casing A, through two holes, a a, one at the top and one at the bottom, as represented. Through these holes the water and the gas circulate freely, so that the water in the chamber A³ is always certain to be exactly on a level with the water in the main casing A.

The chamber A² communicates freely with the chamber A³, at the bottom, but not at the top. It follows that there is a tendency to an equal level of the water in these two chambers, A² and A³.

C is a pipe leading from near the top of the chamber A², down into a lower chamber, A⁴, which is in communication with the gas, and insures the presence of the same or very nearly the same pressure in the top of the chamber A² as in the top of the chamber A³. It follows that the gas will flow in or out through the pipe C, and thus insure that the water-level in the two chambers, A² and A³, is nearly or exactly level one with the other. Any change of level in the water in the main casing A will correspondingly change the level in the two chambers, A² and A³.

D² is a straight pipe, passing through stuffing-boxes at the bottom and top of the casing A³, open at the top into the top of the casing A¹, and open at the bottom into the lower casing A⁴. There is a hole, d, in its side, the upper edge of which is held at exactly the desired water-level in the casing. The pipe D² is capable of being adjusted up and down through the stuffing-boxes by means of a wire, D, which leads out through the top of the casing A¹. It may be either provided with a stuffing-box, not represented, or it may be soldered fast and tight, after having been once satisfactorily adjusted, as may be preferred. Immediately below the hole d, in the side of the pipe D², the interior of the pipe is plugged or stopped by a metallic partition. Consequently, there can be no passage of water downward, but only of gas upward from the casing A³. But there is a branch-pipe lead-

ing away horizontally below the plug or stopping, and bending upward in the chamber A^3 , as indicated by D^2 . The upper end of the branch-pipe D^2 is open, and stands at or very near the level of the upper edge of the hole or opening in the pipe D^3 . This branch-pipe D^2 allows any water entering into it to flow down into the lower casing A^4 , and to be ultimately discharged into the sewer or other suitable receptacle.

It will be seen, that in case the water in the casing A rises above the proper level, a small quantity will overflow into the branch-pipe D^2 , and be discharged downward; while, if the water in the main case A gets too low, the upper edge of the hole or opening d will be exposed above the water-line, and a small quantity of gas will enter the pipe D^3 , and rising freely and flowing out at its top, will add to the quantity of the gas in the top of the fountain or casing A^1 , and will consequently allow a corresponding quantity of water to flow out from this fountain-casing A^1 into the main casing A . I have not found it necessary to provide any special orifice for this flow, there being always sufficient space around the main shaft b .

In adjusting a new meter, I raise or lower the wire D and its connections, until the level is attained at which the meter will register exactly as desired.

The gas, after passing the meter, descends into the lower casing A^4 , where it can drop any water or the like with which it may be accidentally charged, and rises, through the pipe E , into the double chamber $E^1 E^2$, from the uppermost of which it rises, through the pipe E^3 , to be distributed through the house.

The chambers $E^1 E^2$ communicate through a single orifice, controlled by a tight-fitting puppet-valve, G .

This valve is operated by a wire or rod, g , which extends down through the open pipe H , soldered to the lower side of the chamber E^1 , and connects to the lever I , which turns on the centre i , and carries a suitable float, J .

Now, when, by the repeated additions of small quantities of gas to the fountain-casing A^1 , the water has been gradually lowered therein, to maintain the level in the main casing, until it has become nearly of the same level, so that there is danger of the fountain fail-

ing to deliver water promptly, the float J sinks so low as to commence to close the valve G . By means of the powerful leverage obtained, a float of moderate size may control this valve with great firmness, so as to be little affected by the force of the gas. Whether the force be great or small, it will hold the valve very nearly closed, and this condition will soon make itself manifest by the diminished force of the gas in the house. This will be a signal that the fountain-casing A^1 should be refilled by pouring water into the pipe a .

Having now fully described my invention,

What I claim as new, and desire to secure by Letters Patent, is—

1. The fountain-casing A^1 , connected to the casing A , as represented, and arranged to supply water thereto, as required, to maintain an invariable level therein, so long as the water in the fountain is above that level; and also to enclose the mechanism conveying the motion to the registering-wheels, the float and valve, and the regulating-case $A^2 A^3$, and its connections, all substantially as herein set forth.

2. The inner casing $A^2 A^3$, the duplex tube or passage $D^2 D^3$, the part D^2 being open to receive water, and the part D^3 being open to receive gas, as indicated at d , combined and arranged as represented, relatively to the fountain-casing A^1 and the main casing A of a gas-meter, for the purposes herein set forth.

3. Adjusting the tube $D^2 D^3$ up and down through stuffing-boxes, as represented, by means of the wire D or an equivalent connection, leading to the outside of the apparatus, substantially as herein set forth and described.

4. The lever I and float J , in combination with the valve G and connection g , and with a fountain-reservoir, A^1 , for a gas-meter, as and for the purposes herein set forth.

In testimony whereof, I have hereunto set my name, in presence of two subscribing witnesses.

THOMAS BRATTAN.
